UNITED STATES PATENT OFFICE.

DANIEL W. BARTON, OF OSHKOSH, WISCONSIN, ASSIGNOR TO WARREN G. MAXCY, OF OSHKOSH, WISCONSIN.

PIANO ATTACHMENT.

1,174,957.

Specification of Letters Patent. Patented Mar. 14, 1916.

Application filed May 7, 1913. Serial No. 765,987.

To all whom it may concern:

Be it known that I, DANIEL W. BARTON, a citizen of the United States, and resident of Oshkosh, in the county of Winnebago and 5 State of Wisconsin, have invented new and useful Improvements in Piano Attachments, of which the following is a description, reference being had to the accompanying drawings, which are a part of this specification.

10 This invention relates to improvements in piano attachments and more particularly to attachments for controlling the playing of other musical instruments, remotely positioned, at the same time the piano is played.

15 It is one of the objects of the present invention to provide a piano attachment which may be built into and form part of the piano and be actuated by the key mechanism of the piano to play musical instruments remotely positioned.

20 A further object of the invention is to provide a piano attachment in the form of a contact plate which is adapted to be movably mounted within a piano and positioned 25 to be actuated by the key mechanism of the piano when desired while the piano is being played.

30 A further object of the invention is to provide a piano attachment for pianos and other like instruments for electrically actuating musical instruments located exteriorly of the piano.

35 A further object of the invention is to provide a piano attachment which is of simple construction and may be easily mounted within any piano and which is well adapted for the purpose desired.

40 With the above and other objects in view the invention consists of the improved piano attachment and its parts and combinations as set forth in the claims and all equivalents thereof.

45 In the accompanying drawing in which the same reference characters indicate the same parts in all of the views: Figure 1 is a side view of the upper portion of a key mechanism of a piano provided with the improved attachment, a portion of the piano and the attachment being shown in section 50 and an electrical circuit being indicated in diagram. Fig. 2 is a transverse sectional view of a portion of a piano showing a modified form of attachment in position to be actuated by the piano keys; Fig. 3 is a 55 similar view of another modified form of

attachment; Fig. 4 is a similar view of another modification; and Fig. 5 is a top detail view of a fragment of the contact board and part of the action.

Referring to the drawing and particularly to Fig. 1 the numeral 8 indicates a portion of a piano of ordinary construction, 9 one of the piano keys thereof and 10 the key mechanism or action actuated by a pressure on the key.

60 The piano attachment consists of a fixed contact board 11 formed of fiber or other insulating material upon which are mounted a series of spring contact members 12 (only one being shown) positioned to contact with a metal contact strip 13 located above the said contact members when the piano key is depressed. In the form shown in this figure the contact member projects 65 beyond the contact board to a position 70 slightly above one of the upward swinging levers or wippens 14 of the action 10 of the piano and will be moved into contact with the contact strip 13 when the mechanism is actuated by the key. An electric 75 bell or other musical instrument 15 is connected to the spring contact by circuit wire 80 16 and a return wire 17 which includes a source of electrical current 18 connects the common contact strip 13 to the said 85 musical instrument 15 thus completing a circuit when a contact is made.

90 While only one contact member and one musical note or instrument are shown in some of the views it is to be understood that 95 the number of contact members will correspond to the number of musical notes or instruments used.

In the form shown in Fig. 2 the contact board 11 is mounted above the keys 9 and 95 is provided with a spring contact 12' and a contact post 19. Circuit wires 16 and 17' are connected to these parts in the same manner before described with relation to Fig. 1 and the parts are actuated in the 100 same manner by depressing the keys.

105 In the Fig. 3 form the contact board 11' is positioned beneath the piano keys and is mounted on the upper end of a pedal bar 20 controlled by a pedal 21 so that when the pedal is pressed downwardly the contact board will be raised upwardly to permit the piano key to engage the spring contact 12'' and move it against the contact post 19 when the key is pressed down- 110

wardly. The spring contact and the contact post are mounted on the contact board 11' and the circuit wires 16 and 17' are connected in the same manner before described.

In the modified form shown in Fig. 4 the spring contact 12''' is mounted on a vertically moving part or abstract 22 of the piano action 10 and the contact strip 13 is positioned just above the contact so that the upward movement of the piano action will move the contact against the strip and complete the circuit. These parts also have the circuit wires 16 and 17 connected in the same manner before described.

From the foregoing description it will be seen that the piano attachment is of simple construction and may be easily placed within a piano at different points and when properly positioned the operator may play the piano and at the same time play a number of other instruments or may if desired only play the piano.

What I claim as my invention is:

1. In combination, with a piano, an attachment therefor comprising a contact board, an electric circuit including a source and branch circuits and a contact in each branch circuit, said contacts located to be

moved by the key of the piano to complete 30 said circuit, means for moving said contacts into the paths of movement of the keys to be actuated thereby, and a plurality of electrically operated musical instruments, one included in each branch circuit and operated 35 upon the closing of its circuit by the depression of the corresponding piano key.

2. In combination, with the key mechanism of a piano, an attachment therefor comprising a movable member, an electric 40 circuit including a source and branch circuits and a contact in each branch circuit carried by said movable member, said contacts located to be independently actuated by the keys of the piano, a plurality of electrically operated musical instruments, one included in each branch circuit and operated 45 upon the closing of its circuit by the depression of the corresponding piano key, and a pedal connection for moving the movable member to a position to have its contacts engaged by the keys.

In testimony whereof, I affix my signature, in presence of two witnesses.

DANIEL W. BARTON.
